UNITED STATES PATENT OFFICE.

JOHN H. SIEGLE, JR., AND OMER H. ANDREWS, OF AMSTERDAM, NEW YORK.

VALVE-GRINDING TOOL.

1,101,342.

Specification of Letters Patent. Patented June 23, 1914.

Application filed February 12, 1914. Serial No. 818,346.

To all whom it may concern:

Be it known that we, JOHN H. SIEGLE, Jr., and OMER H. ANDREWS, citizens of the United States, residing at Amsterdam, county of Montgomery, and State of New York, have invented certain new and useful Improvements in Valve-Grinding Tools, of which the following is a specification.

The invention relates to such improvements and consists in the novel construction and combination of parts hereinafter described and subsequently claimed.

Reference may be had to the accompanying drawings and the reference characters marked thereon, which form a part of this specification.

Similar characters refer to similar parts in the several figures therein.

Figure 1 of the drawing is a view in central longitudinal section of our improved valve-grinding tool applied to a valve of a gas-engine. Fig. 2 is a view in perspective of the body of the tool and a portion of the swiveled shank. Fig. 3 is a view in perspective of the end of the shank which makes universal swiveled connection with the body of the tool.

The principal object of the invention is to facilitate grinding inaccessibly located valves of gas-engines and the like, without removing the valves.

Referring to the drawing wherein the invention is shown in its preferred form, 1, represents a conical puppet-valve applied to a seat, 2, such as is commonly found in internal combustion engines of automobiles and the like. The valve is provided in its upper side with key-openings, 3, adapted to be engaged by a suitable tool whereby the valve body can be rotated upon its seat to renew and perfect the surfaces of contact between the valve and the seat.

Our improved tool comprises a body, 4, having lugs, 5, adapted to engage the openings, 3, in the valve, and a shank or spindle, 6, having a universal swiveled connection with the body, 4. The body, 4, is provided with a central rectangular opening, 7, in its outer side adapted to receive a head, 8, on

the end of the shank or spindle, 6, which head is of spherical form flattened on four sides, whereby it is adapted to engage the rectangular opening, 7, in various angular positions of the stem rotatively to the axis of the body, 4. The head, 8, is loosely confined within the opening, 7, by means of a plate, 9, secured to the body, 4, by screws, 10, and provided with a central aperture, 11, smaller than the head, 8, and larger than the stem, 6, permitting the stem, 6, to be rocked in different directions while retaining the head, 8, within the openings, 7, and in operative engagement with the rectangular walls of the opening, 7. The shank or stem, 6, may be provided with any desired form of operating handle. We have shown the stem in the preferred form of a brace having the hand-rest, 12, and a crank-handle, 13, formed by a bend in the stem or crank, 6.

In using the device, the body, 4, of the tool is engaged with the valve, 1, the stem, 6, projecting from the body at whatever angle is found convenient, and the tool is then rotated by means of the crank-handle, 13, causing the valve to be rotated upon its seat until the surfaces of the valve and seat are dressed to the desired degree.

What we claim as new and desire to secure by Letters Patent is—

A valve-grinding tool comprising a body having on one end means whereby it is adapted to engage a valve and provided in its other end with an angular opening; and an operating stem having a head substantially in the form of a sphere flattened on its sides engageable with said opening, said body having means whereby said head is loosely confined within said opening with freedom for substantially universal swiveled movement of the stem.

In testimony whereof, we have hereunto set our hands this 29th day of April, 1914.

JOHN H. SIEGLE, Jr.
OMER H. ANDREWS.
